(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a design sixth embodiment thereof; FIG. 7 is a front view of a seventh embodiment thereof; FIG. 8 is a front view of an eighth embodiment thereof; FIG. 9 is a front view of a ninth embodiment thereof; and, FIG. 10 is a front view of a tenth embodiment thereof. The broken lines in the figures show a display screen or portion thereof, and form no part of the claimed design.
